UNITED STATES PATENT OFFICE.

WALTER C. CREDLE, OF FAIRFIELD, NORTH CAROLINA, ASSIGNOR OF ONE-HALF TO
BENJAMIN T. SIMMONS, OF WASHINGTON, DISTRICT OF COLUMBIA.

GUARD FOR VALVES.

Application filed August 6, 1924. Serial No. 730,457.

To all whom it may concern:

Be it known that I, WALTER C. CREDLE, a citizen of the United States, residing at Fairfield, in the county of Hyde and State 5 of North Carolina, have invented certain new and useful Improvements in Guards for Valves, of which the following is a specification.

The object of my invention is to provide 10 an inexpensive device which may be easily applied to a valve and, when applied, will prevent unauthorized opening of the same so that the contents of a tank or pipe line cannot be withdrawn therefrom except by 15 properly authorized persons. The invention also seeks to provide a device for the stated purpose which may be easily adjusted to fit valve casings of different sizes and forms and also to provide such a device 20 which will prevent turning of the pipe line to disconnect the same and thereby permit access to the supply of oil or other commodity. The invention is illustrated in the accompanying drawing and will be herein- 25 after fully set forth.

In the drawing:

Figure 1 is a side elevation of a portion of a tank or reservoir and a pipe line leading therefrom with a controlling valve fitted in 30 the pipe line and equipped with my improved guard, and

Fig. 2 is a transverse section of the guard removed.

In the drawing, the reference numeral 1 35 indicates a reservoir or tank in which oil, gasoline or other liquid commodity is stored, and 2 indicates a pipe line leading therefrom and equipped with a cut-off valve represented conventionally at 3. In carrying out my invention, I employ a housing or casing 4 which is of proper form to fit closely over the handle 5 of the valve and has a permanently closed top or upper end 6 while its lower end is open, as shown at 40 7, whereby it may be easily fitted over the handle and stem of the valve and rest upon the bowl or valve casing. At diametrically opposite points of the housing 4 pairs of perforated lugs 8 are formed thereon, and 45 50 an arm 9 at each side of the housing has its upper end fitted between the respective lugs, the said upper end being formed into an eye 10 through which a pivot pin 11 is inserted, the ends of the pivot pin being upset

against the respectively adjacent lugs 55 whereby the withdrawal of the pin is prevented. The lower end of each arm 9 is formed into a laterally extending perforated lug or eye 12, the opening through which is threaded as will be readily understood on 60 reference to Fig. 2. Below each arm 9 is a bowl-engaging plate 13 provided centrally at its upper edge with a threaded stud 14 engaged through the opening in the respective lug or eye 12 and at the lower end of each 65 of said clamping plates 13 is a perforated depending lug 15 which, when the device is in use, is engaged by the hasp of a padlock 16 or similar locking device. Upon reference to Fig. 2, it will be noted that the arms 70 9 and the plates 13 are of arcuate formation transversely so that they may fit closely to and about the bowl of the cut-off valve so that, when the locking device is engaged through the depending lugs 15, the clamping 75 plates and the arms will be secured snugly about the valve casing or bowl and the housing 4 will be secured in contact with the upper side of the bowl. A chain 17 or its equivalent is engaged with the lock 16 80 and is secured to some permanent part of the pipe line or the tank so that rotation of the pipe line to withdraw it from the tank will be prevented. In the present illustration, the chain is shown as wrapped about one of 85 the legs 18 supporting the tank.

From the foregoing description, taken in connection with the accompanying drawing, it will be seen that I have provided a very simple device which may be easily fitted 90 about the cut-off valve and which, when applied, will prevent access to the valve so that it cannot be opened except by a person having the key of the lock. Unauthorized withdrawal of the contents of the tank will be 95 thereby prevented. The threaded engagement of the studs 14 with the lugs 12 permits the device to be adjusted within certain limits so that one device may be adapted for application to a number of different valves. 100 This adjustability or extensible connection between the upper arms 9 and the lower clamping plates 13 also permits the relative adjustment of these parts so that the proper firm binding of the parts about the valve 105 casing may be easily obtained and the parts cannot be disconnected without first removing the lock so that the plates and arms may

be swung outwardly from the valve casing. It will also be noted that the clamping plates 13 are elongated somewhat so as to extend longitudinally of the valve casing and thereby resist efforts to twist the device about the valve casing to effect disengagement or rupture of some of the parts which would permit removal of the guard from the valve.

10 Having thus described the invention, I claim:

1. A guard for valves comprising a housing adapted to fit over the valve handle and rest upon the valve casing, arms permanently connected to the lower end of the housing at opposite sides of the same and adapted to fit over the valve casing, clamping plates adapted to bear against the lower portion of the valve casing at the opposite sides 20 thereof and connected with the said arms,

and means for locking the clamping plates together about the valve casing.

2. A guard for valves comprising a housing adapted to fit closely over the handle of the valve, arcuate arms pivoted to the lower end of the housing at opposite sides of the same and adapted to bear upon the upper portion of the valve casing and provided at their lower ends with laterally extending threaded lugs, arcuate clamping plates 30 adapted to fit against the lower portion of the valve casing, threaded studs rising from the said clamping plates and engaged through the threaded lugs at the lower ends of the arms, depending lugs at the lower 35 ends of the clamping plates, and a lock engaged with said lugs.

In testimony whereof I affix my signature.

WALTER C. CREDLE. [L. S.]
